UNITED STATES PATENT OFFICE.

CYRUS A. McCAIN, OF BENSONHURST, NEW YORK.

PRINTING-PRESS.

1,225,670.

Specification of Letters Patent.

Patented May 8, 1917.

Application filed January 12, 1916. Serial No. 71,705.

To all whom it may concern:

Be it known that I, CYRUS A. McCAIN, a citizen of the United States, residing at Bensonhurst, in the county of Kings, State 5 of New York, have invented certain new and useful Improvements in Printing-Presses, of which the following is a specification.

The present invention relates generally to printing presses which employ a rotary 10 sheet-carrying cylinder, and more particularly to the various mechanisms for guiding and engaging the sheet of paper to hold it upon the cylinder during its rotations and to free it therefrom at the proper time, as 15 will more fully appear hereinafter.

The various features of my invention may be used in connection with presses of many 20 different types. In the present instance I have chosen to disclose my invention in connection with a flat bed cylinder press of the type in which a rotary impression cylinder 25 co-operates with a flat type bed, the cylinder being moved toward and from the bed as the latter is reciprocated. A clearer understanding of the features of the invention as 30 herein embodied, may be had if it is kept in mind that in such presses two revolutions of the impression cylinder are necessary to print a single sheet; that the delivery of the 35 sheet to the cylinder, the printing of it and the starting of it from the cylinder, are accomplished in a little more than one revolution of the cylinder, that is, during a rotary movement including the first revolution 40 and a small portion of the second, and that during the balance of the second revolution the cylinder is free of a sheet and the bed is on the return stroke.

In the accompanying drawing, Figure 1 45 is an end elevation of a flat bed printing press impression cylinder and associated sheet-handling mechanism constructed in accordance with my invention; Fig. 2 is a plan view of a portion of said cylinder and mechanism; Fig. 3 is a fragmentary transverse section of a portion of the cylinder, the plane of section being indicated by the line 3-3 of Fig. 4; Fig. 4 is a fragmentary plan view of the cylinder illustrating other parts 50 of the sheet-controlling mechanism; Figs. 5 and 6 are detail views of different parts of a spring-actuated gripper pin; Fig. 7 is a view similar to a portion of Fig. 4, illustrating

particularing the tumbler and its actuating pin in position to throw the tumbler; 55 Fig. 8 is a view similar to Fig. 7, but showing the pin in its retracted position; Fig. 9 is an elevation of a portion of the cylinder showing the tumbler and the gripper pin in a position corresponding to that of Fig. 7; 60 and Fig. 10 is a similar view illustrating the pin and tumbler in a position similar to that of Fig. 4. Throughout these views like characters refer to like parts.

The present invention may be considered 65 in general as comprising improvements upon the mechanisms of United States patent to Miehle, No. 574,207, dated December 29, 1896. Because of the similarity of the functions of the present improvements 70 and the functions of the corresponding mechanisms of the Miehle patent, it has been possible to greatly reduce the amount of illustration and description in the present application from what would have been 75 otherwise necessary.

Referring to the drawings in detail, 10 designates a portion of an upright extension of the main frame of a press upon which one of the journal boxes 11 of the 80 impression cylinder 12 is located. A corresponding extension and journal box is located at the other end of the cylinder in the usual manner. The extensions 10 carry guide rod frames 13 and these guide rod 85 frames are connected by a transverse drop guide bar 14, a feed guide rod 15, a stripper finger rod 16, and a conveyer shaft 17. As shown in Fig. 4, the cylinder 12 is provided with a hollow interior cavity 18 in which 90 are located the usual gripper shaft 19 and shoo-fly finger rod 20. The shaft 19 carries the usual grippers 21, and the rod 20 carries the usual lifting or shoo-fly fingers 22. The grippers 21 co-operate with the adjacent 95 edge of the cylinder to hold the sheet while the fingers 22 pass beneath the sheet and at the appropriate time lift the edge of it from the cylinder to be engaged by the stripping fingers 23 located upon the stripping finger rod 16. The gripper shaft 19 is provided with a tumbler 24 which co-operates with a pair of gripper pins 25, 26, to bring about a proper actuation of the grippers 21. The guide rod 14 carries the usual 100 drop guides 27, and the feed guide rod 15

carries the usual front feed guides 28. A fixed arm 29 projecting forward from the guide rod 14 is employed to rock the latter in response to actuations of the link 30 which is secured to its forward end. The guide rod 15 carries a fixed arm 31 and a loose arm 32. The latter which is free to rotate on the rod 15, is angular in shape, as clearly illustrated in Fig. 2, and carries at its forward end a cam roller 33 which travels upon a cam 34 which is secured to the gear wheel 35 mounted upon the journal of the cylinder. A spring pressed pin 36 is mounted upon the loose arm 32 and is movable under its spring pressure, when unrestrained, to pass beneath the outer end of the fixed arm 31. By this construction the arms 31 and 32 are coupled together and as the arm 32 is raised at its outer end, the arm 31 is likewise raised to rock the guide rod 15 and raise the guides 28 located upon it. In order to actuate the pin 36, a member 37 is pivoted to the outer end of the loose arm 32 and arranged to engage at its free end in a notch 38 cut in the side of the pin 36. A cam face 39 is formed at the lower edge of the member 37 to provide for its actuation as hereinafter explained. The stripping finger rod 16 is provided with an arm 40 and the outer end of this arm is connected by a spring 41 to a fixed portion of the guide frame 13 so as to normally hold the stripping fingers 23 down in position to strip the sheet from the cylinder. The movement of the arm 40 and rod 16 in the opposite direction, is brought about by means of a link 42 which is connected to the outer end of the arm.

In the operation of these parts the sheet is fed from the left, as viewed in Fig. 1, and is engaged by the grippers 21 which are actuated through the agency of the closing gripper pin 25 and the associated tumbler 24 upon the gripper shaft 19. Just before the grippers 21 close upon the sheet, the front feed guides 28 are raised. At this time the opening gripper pin 26 is not in tumbler engaging position and therefore as the cylinder rotates, the grippers hold on to the sheet and carry it around to be printed. The sheet continues in engagement with the cylinder until the tumbler 24 of the gripper shaft 19 comes into engagement with the opening pin 26 which has in the meantime been thrown into tumbler engaging position while the gripper closing pin 25 has been thrown out of tumbler engaging position. As the sheet is thus carried about the cylinder, the stripper fingers 23 are elevated. At the time the opening pin 26 engages the tumbler to release the sheet, the stripper fingers 23 are lowered and just before the sheet reaches the stripper fingers, the shoo-fly fingers 22 lift the edge of the sheet on to the points of the stripping fingers 23.

From the latter the sheet is delivered to the conveyer 83. It will be noted that the sheet is held upon the cylinder by the grippers for one complete revolution and a portion of a second revolution, and that the sheets are fed every second revolution of the cylinder. The portion of the second revolution during which the sheet is held by the grippers, is equal approximately to the distance between the gripper pins 25 and 26.

The gripper pins 25, 26, the guide bar actuating link 30, the stripper bar actuating link 42, and the cam member 37 for actuating the coupling pin 36 to bring the front feed guides into operation, are all operated by means of a reciprocating bar 43 which moves to and fro upon a guide bar 44 which is fixed to the guide frame 13. The employment of this bar 43 to actuate the gripper and other mechanisms, constitutes an important feature of my invention. This reciprocating bar 43 is actuated by means of a bell crank lever 45 which is pivoted at 46 to a portion of the guide frame 13 and is provided at its opposite end with an elongated shoe 47 which engages a cam track located upon the one face of the wheel 35, which comprises an inner portion 48 and an outer portion 49 which come together, as clearly illustrated in Fig. 1. During one revolution of the cylinder the shoe 47 travels in the inner cam track 48, and during a second revolution it travels in the outer cam track 49. By this construction the reciprocating bar 43 is moved to one end of its movement as the shoe passes from the inner track 48 to the outer track 49, and to the other end as it passes from the outer track 49 to the inner track 48. To provide for proper action between the bell crank lever 45 and the reciprocating bar 43, the latter is provided with a slot through which the end of the bell crank lever extends and that end of the bell crank is curved so as to provide a sort of ball-and-socket connection with the bar.

The bar 43 is provided at its opposite ends with oppositely inclined slots 50 and 51, the former being associated with gripper pin 25 and the latter with gripper pin 26. In each instance these gripper pins are made up of an outer sleeve 52 and an inner pin 53. The former is provided at one end with a slot 54 and the latter with a similar slot 55. These slots are made for the purpose of embracing the adjacent end of the reciprocating bar 43. A pin 56 holds the parts together. For this purpose it passes through slots 57 of the inner pin member 53 and through the inclined slot 50 or 51 of the bar 43. It is firmly held in position by being secured at its ends to the outer pin member 52. By reason of the slot 57, the inner pin member 53 is movable relative to the outer sleeve 52. In order to hold the parts dis-

tended, that is, in the position illustrated in Figs. 7 and 8, the inner pin member 53 is provided with a central cavity or bore 58 of a diameter approximately equal to the width of the slot 55, and this bore terminates in a smaller bore 59, as clearly illustrated in Fig. 6. A pin 60 having a head 61, is fitted into the smaller bore 59, and a spring 62 is coiled about the pin 60 and lies within the bore 58, bearing at one end against the pin head 61 and at the other end against the end of the bore 58. When the parts of the pin are assembled upon the reciprocating bar 43, the head 61 of the pin 60 bears against one edge of the bar 43 and thereby forces the inner pin member 53 away from the bar 43 until the pin 56 engages the end of the slot 57, as illustrated in Fig. 7. The completely assembled gripper pins 25, 26, are mounted in bearings 63 formed in the guide frame member 13, as clearly illustrated in Fig. 4. They are arranged to coöperate with the tumbler 24 as usual.

25 The gripper tumbler is provided with two oppositely disposed pin-engaging slots 64 and 65 which are separated by a central interposed partition 66. The portion of the tumbler in which the slot 64 is located is shorter than that in which the slot 65 is located, and consequently the end of the latter is farther from the center of rotation of the tumbler. This difference in length is provided so as to enable the longer end to engage the usual stop pins 67 and 68 upon the adjacent portion of the cylinder as the tumbler is rotated back and forth between the positions of Figs. 9 and 10. This to-and-fro rotation of the tumbler is brought about by 35 the gripper pins 25 and 26 engaging the slots of the tumbler in a manner well known in this art. In addition to the slots 64 and 65, the tumbler 24 is provided with central convex, preferably conical, faces 69 and 70, which coöperate with pins 25 and 26 to prevent breaking the latter in case the tumbler is not in the proper position, as sometimes occurs when the pressman is turning over the cylinder preparatory to putting the 40 press in operation. In normal operation the closing pin 25 enters the slot 64, and the opening pin 26 enters slot 65, in the manner illustrated in Fig. 9. However, if the tumbler should not be in pin-receiving position, that is, in position for the appropriate gripper pin to enter the appropriate slot 64 or 65, but in a position such as that illustrated in Fig. 10, then the inner member 53 of the pin upon engaging the inclined conical face 69 or 70 of the tumbler, would be pressed back by the latter against the pressure of its spring 62, in the manner illustrated in Fig. 4, and would ultimately pass out of engagement with the tumbler without 45 being broken. This tumbler and pin con-

struction constitutes an important feature of my invention.

As the reciprocating bar 43 is moved back and forth, the relative positions of the outer and inner members 52 and 53 of the pin do not change so long as the inner member 53 does not engage one of the inclined faces of the tumbler, but the pin as a whole moves back and forth in its bearing 63, as clearly illustrated in Figs. 7 and 8. Under these conditions the pin 56 of the gripper pin structure remains always in engagement with the outer end of the slot 57 of the inner pin member 53, while the position of the bar 43 in the slots 54 and 55 of the pin members varies, as will be apparent from a consideration of Figs. 4, 7 and 8.

The grippers 21 are of the usual construction and are sleeved upon the gripper shaft 19 and held in proper position by set-screws 80 71. They are yieldingly held either in closed position or in wide open position by means of the usual spring toggle construction in which an arm 72 securely clamped to the shaft 19 by bolts 73, is pivotally connected 90 at its outer end to one end of a rod 74 which passes through an eye-bolt 75 secured to a suitable point in the interior of the cylinder and in which a spring 76 acts between the eye-bolt 75 and a collar 77 upon the rod 74. 95 The compression of the spring 76 may be varied by shifting the collar 77 upon the rod in a well known manner. With this construction the parts are so positioned that the pivotal connection between the arm 72 and 100 rod 74 will lie on either side of a plane through the shaft 19 and the eye-bolt 75. This is the usual construction for this purpose and need not be further illustrated. It is practically identical with that shown in 105 Fig. 8 of the aforesaid Miehle patent. From this description it will be seen that in operation, when a gripper pin, such as 25, engages one of the slots of the tumbler 24, the latter will be rotated so as to shift the pivotal connection between the arm 72 and the rod 74 beyond center, and thereby allow the spring 76 to complete the movement of the gripper shaft 19. The stop pins 67, 68, of course limit the movement of the shaft 19 in 110 either direction.

The reciprocating bar 43 serves to actuate the drop guides by means of a projection or block 78 located upon its upper surface and arranged to engage the free end of the 120 link 30 carried by the arm 29, as before explained. As the bar 43 moves to the left, viewing it as shown in Fig. 1, the arm 29 and fingers 27 are raised. As the bar moves to the right, the corresponding parts are lowered. This lowering movement is limited by the engagement of a stop pin 79 with the upper face of the hub of the loose arm 32 upon rod 15 previously referred to. This stop pin 79 is in the form of a screw 125 130

threaded through a boss upon the arm 29 and held in adjusted position by means of a lock-nut 80.

The stripper fingers 23 are moved out of sheet-engaging position by means of a similar block or projection 81 upon the reciprocating bar 43, which is arranged to engage the free end of the link 42. When the bar 43 is moved to the right, as viewed in Fig. 1, the projection 81 by pressing upon the link 42, rocks the stripper finger rod 16 against the pressure of the spring 41 and thereby raises the stripper fingers 23. As the reciprocating rod moves in the opposite direction, the spring 41 causes a return of the stripping fingers. The arm 40 is secured upon the shaft 16 in desired position by a set-screw 107.

The projection 81 upon the reciprocating bar 43 also coöperates with the cam face 39 upon the cam member 37 by which the clutch pin 36 coöperating between the fixed and loose arms 31 and 32 upon the rod 15, couples them together so as to act in response to the movements of the loose arm 32. As the bar 43 is moved to the left, as viewed in Figs. 1 and 2, the projection 81 by moving along the cam face 39, allows the spring pressed member 37 to move the pin 36 against the tension of its spring out of engagement with the fixed arm 31 and thereby allows the feed guides 28 to be lowered. Its movement in the opposite direction depresses the cam member 37 against the tension of its own spring and allows the spring of the pin 36 to force the latter into engaging position, with the result that as the loose arm 32 is raised at its outer end, the fixed arm 31 will also be raised and the rod 15 rocked to raise the guides 28.

In the preferred construction I employ sheet guides or brushes 82, which are hung upon a transverse rod 82^a extending between extensions 82^b of guide rod frames 13. These brushes 82 engage the sheet to hold it against the cylinder as the latter carries it around. When the sheet is stripped from the cylinder by the stripping fingers 23, it is carried upon conveyer tapes 83 which pass over conveyer wheels mounted upon the conveyer shaft 17. This shaft is preferably driven through a train of gearing from the large cylinder gear wheel 35. This train of gearing includes a gear wheel 85 keyed to the shaft 17 and meshing with a gear wheel 86 keyed to a stud 87 upon which the gear wheel 88 is also keyed. This latter gear wheel is in line with the gear wheel 35 and is adapted to be driven from it. The conveyer constitutes no part of the present invention and is only incidentally shown. This is also true of the sheet guides 82.

The lifting fingers 22 are of the usual construction and they are provided with hubs which are mounted on the shoo-fly

shaft 20 and held in position by set-screws 90 in the usual way. This shaft 20, however, is arranged so that the fingers 22 may be thrown up by hand into a position where the other parts of the mechanism in the interior of the cylinder may be readily inspected or be rendered more accessible to the operator. It is also divided into sections and so arranged that that section which contains the fingers may be readily removed from the cylinder by hand. For this purpose I divide the shaft into a short section 91 which extends only through the adjacent end web of the cylinder and a longer section 92 which extends practically throughout the length of the opening 18 in the cylinder. It is upon the latter section that the fingers 22 are mounted. The end of the shaft section 92 enters a small bearing cavity 93 in the end web distant from the section 91 so that it may be readily slipped into and out of said bearing. The other end of the section 92 is provided with a coupling member 94 which coöperates with a coupling member 95 upon the adjacent end 90 of the section 91. These coupling members are rigidly secured to their respective sections by pins 96, 97, and a spring pin 98 carried by the member 94 engages an opening in the member 95 to hold the coupling members together. By simply drawing out the pin 98 from its opening in the clutch member 95, section 92 may be rotated so as to lift the fingers 93 up out of engagement with the cylinder, or the entire section with its fingers may be removed by drawing upward upon the end of the section adjacent to the coupling and then withdrawing the other end from its bearing 93. The outer end of the shaft section 91 is provided with the usual shoo-fly lever 99 and associated cam-roller 100. These coöperate with the shoo-fly cam 101 which is suitably pivoted upon a transverse shaft 89 which extends between and is supported by the guide frames 13. 110

A leaf spring 102 secured to a pin 103 upon one end of the cylinder 12, bears at its free end against the outer end of the cam lever 99 and tends to hold the latter against a stop pin 104 located in the adjacent end 115 of the cylinder 12. A similar pin 105 positioned below the spring 102 and nearer to its supporting pin 103, serves to prevent undue downward flexure of the spring 102. The construction by which the shaft 20 and fingers 22 may be removed from the cylinder, or, in the alternative, the fingers rocked so as to give access to the parts within the cylinder, is an important and desirable feature of my invention. 120

The mechanism for operating the shoo-fly shaft 20 may be of any desired construction. Preferably, however, I locate a cam stop 106 upon the shaft 16 and just inside of the adjacent frame 13. When the strip- 130

ping fingers 23 are elevated and the sheet is passing around to be printed, the stop 106 is rotated by the link 42 so as to clear a stop 108 upon the cam 101. This is the 5 position shown in Fig. 1 in full lines. As a result, the cam 101 swings outward about shaft 89 by reason of the pressure of the cam roller 100 as the latter engages the face 109 of the cam and the shoo-fly fingers 22 are not raised. On the next revolution of 10 the cylinder, the stripper shaft 16 is not rocked but the stop 106 is left in position to be engaged by stop 108 on cam 101, as 15 illustrated in the dotted line position in Fig. 1. Consequently the cam 101 is held from swinging and therefore the roller 100 as it engages the face 109, is depressed, and fingers 22 lift the edge of the sheet upon the ends of the stripping fingers 23.

20 In carrying out my invention it will be apparent that many alterations and modifications may be made in the specific structures herein disclosed without departing from the spirit and scope of the invention. 25 I therefore do not wish to be limited to the precise structures illustrated and described, but aim to cover all such alterations and modifications by the terms of the appended claims.

30 What I claim as new and desire to secure by Letters Patent of the United States is:

1. Printing press mechanism comprising a cylinder, sheet grippers on said cylinder, a gripper shaft, a tumbler on said shaft, 35 gripper pins for engaging said tumbler to actuate said shaft, a reciprocating sliding bar having oppositely inclined slots, a guide bar along which said reciprocating bar travels, pins in said gripper pins extending 40 through said slots, and means for actuating said bar in response to the rotations of said cylinder.

2. Printing press mechanism comprising a cylinder, sheet grippers on said cylinder, 45 a gripper shaft, a tumbler on said shaft, gripper pins for engaging said tumbler to actuate said shaft, a reciprocating sliding bar having oppositely inclined slots, a guide bar along which said reciprocating bar 50 travels, pins in said gripper pins extending through said slots, an oscillating lever to reciprocate said bar and actuate said pins, a wheel rotatable with said cylinder, a cam shoe on said oscillating lever, and a cam 55 groove on said wheel for coöperating with said shoe to oscillate said lever.

3. Printing press mechanism comprising a cylinder, sheet grippers on said cylinder, a gripper shaft and tumbler on said shaft, 60 and a pin for engaging said tumbler, said tumbler having two oppositely disposed open-ended grooves separated by a central interposed partition and having a central conical surface outward of said grooved 65 portions, said surface having its conical

axis concentric with the axis of said gripper shaft, said grooves being for the reception of the pin in normal operation and said convex surface being to ward off the pin when engaged while not in receiving position and said pin being mounted to yield in response to the pressure exerted by said conical face. 70

4. Printing press mechanism comprising a cylinder, sheet grippers on said cylinder, 75 a gripper shaft and tumbler on said shaft, and a pin for engaging said tumbler, said tumbler having two oppositely disposed open-ended grooves separated by a central interposed partition and having a central 80 conical surface outward of said grooved portions, said surface having its conical axis concentric with the axis of said gripper shaft, said grooves being for the reception of the pin in normal operation and said 85 convex surface being to ward off the pin when engaged while not in receiving position, and said pin having two relatively movable parts normally held distended by an interposed spring. 90

5. A tumbler for gripper mechanisms comprising two oppositely disposed pin-engaging slots and a central conical face outward of said slots for warding off the pin when said tumbler is engaged while not in receiving position, said conical face having its conical axis extending at right angles to the plane of said tumbler and intersecting the same at a point between said slots. 95

6. Printing press mechanism comprising 100 a gripper pin having two telescoping parts, a spring interposed between said parts, a pin in one part coöperating with a slot in the other to limit their relative movements, and a reciprocating bar for actuating said pin, said bar having a diagonal slot through which said pin passes. 105

7. Printing press mechanism comprising a cylinder, sheet grippers, stripping fingers, 110 a gripper shaft, a finger bar, a tumbler on said shaft, gripper pins for engaging said tumbler to actuate said shaft, a reciprocating member, means for actuating said reciprocating member in response to the rotations of said cylinder, and means acting between 115 said member and bar and pins to actuate said pins and rotate said finger bar in response to the reciprocations of said member.

8. Printing press mechanism comprising a cylinder, sheet grippers, a gripper shaft, 120 stripping fingers, a bar for supporting said fingers, a tumbler on said shaft, gripper fingers for engaging said tumbler to actuate said shaft, a reciprocating sliding bar, a guide along which said bar slides, an arm 125 on said finger supporting bar, a link secured to the outer end of said arm and extending into engagement with said sliding bar, means for reciprocating said sliding bar in response to the rotations of said cylinder, 130

means on said sliding bar for engaging said link to actuate said stripping finger bar, and pin-and-slot connections between said sliding bar and said gripper pins to actuate the latter upon the reciprocations of the former.

9. Printing press mechanism comprising a cylinder, sheet grippers, a gripper shaft, stripping fingers, a bar for supporting said fingers, a tumbler on said shaft, gripper fingers for engaging said tumbler to actuate said shaft, a reciprocating sliding bar, a guide along which said bar slides, an arm on said finger supporting bar, a link secured to the outer end of said arm and extending into engagement with said sliding bar, means on said sliding bar for engaging said link to actuate said finger stripping bar, pin-and-slot connections between said sliding bar and said gripper pins to actuate the latter upon the reciprocations of the former, an oscillating lever to reciprocate said sliding bar, a wheel rotatable with said cylinder, a cam shoe on said oscillating lever, and a cam groove on said wheel for coöperating with said shoe to oscillate said lever.

10. Printing press mechanism comprising a cylinder, sheet grippers, a gripper shaft, stripping fingers, a bar for supporting said fingers, a tumbler on said shaft, gripper fingers for engaging said tumbler to actuate said shaft, a reciprocating sliding bar, a guide along which said bar slides, an arm on said finger supporting bar, a link secured to the outer end of said arm and extending at its free end into engagement with the upper side of said sliding bar, means for reciprocating said sliding bar in response to the rotations of said cylinder, a projection on the upper side of said sliding bar for engaging the free end of said link to actuate said stripping finger bar as said sliding bar is actuated, and connections between said sliding bar and said gripper pins for actuating the latter as said sliding bar is reciprocated.

11. Printing press mechanism comprising a cylinder, sheet grippers, sheet guides, stripping fingers, a gripper shaft, a guide bar, a stripping finger bar, a tumbler on said shaft, gripper pins for engaging said tumbler to actuate said shaft, a reciprocating member, means for moving said reciprocating member to and fro in response to the rotations of said cylinder, arms extending from said guide bar and finger bar respectively, links secured to the outer ends of said arms respectively and extending into operative engagement with said reciprocating member, means for causing said links to rotate said guide bar and finger bar as said member is reciprocated, and connections for actuating said gripper pins in response to the reciprocations of said member.

12. Printing press mechanism comprising a cylinder, sheet grippers, a gripper shaft, sheet guides, a guide bar for supporting said guides, a tumbler on said shaft, gripper fingers for engaging said tumbler to actuate said shaft, a reciprocating sliding bar, a guide along which said bar slides, an arm on said guide bar, a link secured to the outer end of said arm and extending at its free end into engagement with the upper side of said sliding bar, means for reciprocating said sliding bar in response to the rotations of said cylinder, a projection on the upper side of said sliding bar for engaging the free end of said link to actuate said guide bar to move said sheet guides, a stop for limiting the downward movement of said sheet guides independently of the position of said reciprocating sliding bar, and connections between said sliding bar and said gripper pins to actuate the latter upon the reciprocations of the former.

In testimony whereof I have hereunto subscribed my name this 10th day of January, A. D. 1916.

CYRUS A. McCAIN.

Copies of this patent may be obtained for five cents each, by addressing the "Commissioner of Patents, Washington, D. C."
